UNITED STATES PATENT OFFICE.

GEORGE S. PRUDEN, OF PATERSON, NEW JERSEY, ASSIGNOR TO PAUL GERLI, OF NEW YORK, N. Y.

LOOM.

1,003,202.

Specification of Letters Patent. Patented Sept. 12, 1911.

Application filed February 24, 1910. Serial No. 545,636.

To all whom it may concern:

Be it known that I, GEORGE S. PRUDEN, a citizen of the United States, residing at Paterson, in the county of Passaic and State 5 of New Jersey, have invented certain new and useful Improvements in Looms, of which the following is a full, clear, and exact description, such as will enable others skilled in the art to which it appertains to 10 make and use the same.

This invention relates to looms and with regard to the more specific features thereof to apparatus of this character for weaving neckties and similar articles.

15 One of the objects thereof is to provide a practical and efficient loom adapted to change the width of the woven article in any portion thereof by changing the spreading of the warp threads and to simultaneously change the spacing of the weft threads in inverse ratio.

Other objects will be in part obvious and in part pointed out hereinafter.

The invention accordingly consists in the 25 features of construction, combinations of elements and arrangement of parts which will be exemplified in the construction hereinafter set forth, and the scope of the application of which will be indicated in the 30 following claims.

In the accompanying drawing, wherein is shown one of various possible embodiments 35 of this invention, Figure 1 is a diagrammatic side view of a loom; Fig. 2 is a partial front elevation of the loom batten showing the reed frame in operative relation therewith; Fig. 3 is a cross section of the batten taken on line $x-x$ of Fig. 2; Fig. 4 is a front view of one of the reeds; Fig. 5 is a

40 plan view of the right hand end of the parts shown in Fig. 2; Fig. 6 is an enlarged detail view of a device to be hereinafter described.

Similar reference characters refer to similar parts throughout the several views of 45 the drawings.

Referring to the drawings, 1 denotes the loom-frame from which is suspended by means of a bracket 2 and bolt 3, the arms 4 which have secured to the lower ends thereof, 50 a horizontally extending batten 5 provided with shuttle-guides 6 and having attached to the back thereof two angular members 7 between which the reed-frame 8 is slidably secured. A plurality of inverted

fan shaped reeds 8' are secured to the frame 55 8 and the latter part is suspended from rocker-arms 9 by means of wires 10. The said rocker-arms are fastened to a rock-shaft 11 which extends across the top of the machine, supported upon the frame 1 by means 60 of brackets 12. A rocker arm 13 extends in the opposite direction from the rock-shaft and is fastened thereto. A wire 14 serves to connect the arm 13 with a pivotally mounted lever 15 supporting thereon a cam wheel 16. 65 A shaft 17 journaled in any suitable manner has secured thereon a double cam 18 and also a gear wheel 19, the latter adapted to be driven by means of intermediate gearing 20 by a pinion 21 secured to a shaft 22. A 70 ratchet wheel 23 also secured to the shaft 21, has in engagement with the teeth thereof, a pawl member 24 pivoted to a ratchet arm 25 loosely journaled upon said shaft 21. A wire 26 connects the end of this ratchet 75 arm with one branch of a bell-crank lever 27, the other branch of which is connected to one of the batten arms 4 by means of a wire 28. A drive shaft 29 is suitably journaled upon the frame of the machine and 80 has fastened thereto a crank disk 30 provided with a crank pin 31, a pitman 32 journaled at one end upon said pin is provided at the other end with a pin 33 adapted for adjustment within a slotted member 34 secured to the batten 5.

35 denotes the spools from which the warp threads 36 are led around suitable journaled rods 37 whence said warp passes forwardly between the shuttle blocks 6 90 around a pulley rod 38, thence to the cloth beam 39 upon which the woven articles are wound.

40 indicates the points where the heddles, not shown, engage the warp. 95

Secured upon the end of the shaft 11 is a forwardly extending arm 41 and suspended from said arm by wire 42 is a rod 43, adapted to slide within a tubular guide 44 fastened to the front of the batten 5, at 100 one end thereof. A similar tubular guide 44' is secured to the batten alongside of guide 44 and slidably disposed therein is a rod 43' provided with a pin or bolt 45 which extends through a slot 46' in the 105 face of guide 44'. A spring 54 secured to the lower end of rod 43 exerts a downward pull thereon and prevents the wire 42 from

becoming slack when the rocker arm 41 moves downwardly. Secured to the rod 43 in any suitable manner, as by a stud bolt 55, a bar 56 is provided, which extends 5 transversely from said rod in the direction of and in close proximity to the face of guide 44'. When the rod 43 is lifted the said bar 56 will rise into contact with the pin 45 and the continued upward movement of the rod 43 will impart a similar movement to rod 43'. A collar 57 adjustably secured to rod 43' by means of a set screw 58 is provided to limit the downward movement of the rod 43' upon said collar 10 coming into engagement with the top of the guide 44', whereby a limited movement of rod 43' may be had irrespective of the distance through which rod 43 drops. A ratchet 47 engages the ratchet wheel 48 secured upon a shaft 49 and gearing 50 transmits the motion of the shaft 49 to the cloth beam 39. Connecting the ratchet 47 with the pin 45 is a cord 51 which is held in any suitable position by means of a pulley 52. 15 A spring 53 also connected at one end to the said ratchet 47 extends in a direction opposite to the cord 51 and has its other end secured to the floor, as shown, or if desired, to a portion of the frame 1. 20 Having described the present embodiment of this invention, the operation thereof, which is largely obvious, follows: The warp having been properly drawn into the heddles and the end thereof operatively 25 connected to the cloth beam 39, upon rotation of the drive shaft 29, a swinging motion is imparted to the batten 5. With the swinging of the batten the shuttle moves in the shuttle blocks 6 in the usual manner 30 to lay the weft thread or filling in the warp. Suitable heddles, not shown, separate the elements of the warp to give the desired weave, which may be single, double or tubular in accordance with the kind of 35 finished article desired. The warp threads pass through the dents in the reed and, by raising or lowering the latter, the said threads may be spaced farther apart or drawn closer together, as the case may be. 40 Hence if a necktie having a narrow neck portion is to be woven, the reed is gradually lowered after the proper length of end has been formed and the narrowing of the tie assumes a regular tapered form until 45 the desired width is attained, when, because of the shape of the cam the reed is held substantially stationary during the weaving of the neckband, after which the reed is gradually raised and the tie widened 50 to form the other end portion thereof. As the batten swings a rotary motion is given to the cam 18 by means of the ratchet 25 and the intermediate gearing. The cam in rotating acts upon the wheel 16 to depress 55 the lever 15. The motion of this lever is

transmitted to the rock shaft 11 and the rocker arms 41 and 9 are raised or lowered. Starting with the cam in position shown in Fig. 1, the weaving begins at the short end of the tie and continues forming the full width thereof until the narrower portion of the cam engages the wheel 16, when the reed is gradually lowered and the tie narrowed. Then as the wheel 16 rides upon the opposite end of the cam, the tie widens 70 again and the long end thereof is formed. It is to be noted that in the present embodiment the cam is made double so that during a complete revolution thereof, the reed is moved to control the weaving of 80 two complete ties. With the closer spacing of the warp threads it becomes necessary to proportionately increase the spacing of the weft threads to prevent the tie in its narrower portion from becoming too thick and 85 stuffy. This is accomplished by increasing the rate of feed of the warp through an increased rotation of the cloth beam. As the batten swings a rocking movement will be given the ratchet 47 which imparts a partial rotation to the cloth beam with every such swing of the batten. By permitting the pin 45 to assume a lower position relative to the batten, the said pin will swing 90 through a greater arc and consequently 95 give an increased movement to the cloth beam. Since this lowering of the pin 45 results from the downward movement of rod 43, it is accomplished simultaneously with the lowering of the reed frame, as the 100 rocker arm 41 shares with the arm 9, the movement imparted thereto by the cam 18. The number of ties that may be simultaneously woven corresponds to the number of 105 separate warps drawn into the loom, which depends upon the number of reeds and shuttles with which the loom is equipped.

It is obvious that many advantages arise from the use of a double cam and prominent among these is the fact that the ties formed from each warp will be joined alternately short end to short end and long end to long end, thus facilitating the cutting apart of the ties, as in each instance the cut will be made at the center of the wider portions 115 of the strip wound upon the cloth beam.

From the foregoing it will be seen that the present device is one well adapted to accomplish, among others, all of the ends and objects hereinbefore set forth, in a practical and efficient manner, and to achieve many advantages in the operation and construction thereof because of the exceeding simplicity of its various parts.

As many changes could be made in the above construction and many apparently widely different embodiments of this invention could be made without departing from the scope thereof, it is intended that all matter contained in the above description or 125 130

shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, 5 might be said to fall therebetween.

Having described my invention, what I claim as new and desire to secure by Letters Patent is:

1. In a loom for weaving neckties, in combination, a batten over which a warp is adapted to be fed, provided with shuttles adapted to lay the weft within said warp, means for swinging said batten, a cloth beam, a cam connected to be rotated by the 15 swing of said batten, and means movably mounted on said batten and controlled in its movement by said cam adapted to drive said cloth beam at different rates of speed.

2. In a loom for weaving neckties, in combination, a batten over which a warp is adapted to be fed, provided with shuttles adapted to lay the weft within said warp, means for swinging said batten, a cloth beam, a cam adapted to be actuated by the 20 swinging of said batten, a rocker arm adapted to be rocked by said cam and means for driving said cloth beam adapted to swing with said batten and to be raised and lowered by said rocker arm, whereby the feed 30 of the warp and the spacing of the weft thread is controlled.

3. In a loom for weaving neckties, in combination, a batten over which a warp is adapted to be fed, provided with shuttles 40 adapted to lay the weft within said warp, means for swinging said batten, a cloth beam, a double cam adapted to be rotated by the swinging of said batten, a rock shaft which receives movement from said cam, 45 an arm secured thereto, a member suspended from said arm and slidably mounted upon said batten to swing therewith, a ratchet actuated by said member and means adapted to transmit motion from said ratchet 50 to said cloth beam, whereby every swinging movement of said batten produces a partial rotation of both said cloth-beam and said cam, the extent of the movement of the former being controlled by the conformation 55 of the latter.

4. In a loom for weaving neckties, in combination, a batten over which a warp is adapted to be fed, provided with shuttles adapted to lay the weft within said warp, 60 means for swinging said batten, a fan shaped reed through which said warp passes, adapted to be raised and lowered in relation to said batten for changing the width of the warp, a cloth-beam adapted to feed said 65 warp, a cam adapted to be actuated by the

swinging of said batten, and means adapted to be moved in accordance with the conformation of said cam to raise and lower said reed and to control the movement of said cloth-beam, whereby the spacing of the weft threads per unit of length of the tie will be varied simultaneously with the changing of the width thereof by the movement of said reed.

5. In a loom for weaving neckties, in combination, a batten over which a warp is adapted to be fed, provided with shuttles adapted to lay the weft within said warp, means for swinging said batten, a fan shaped reed through which said warp 70 passes, adapted to be raised and lowered in relation to said batten for changing the width of the warp, a cloth-beam adapted to feed said warp, a cam adapted to be actuated by the swinging of said batten, and means adapted to be moved in accordance with the conformation of said cam to raise and lower said reed and to control the movement of said cloth-beam, whereby the spacing of the weft threads per unit of length 75 of the tie will be varied simultaneously with the changing of the width thereof by the movement of said reed, said cam being so formed that every revolution thereof will control the weaving of two complete neckties.

6. In a loom for weaving neckties, in combination, a batten over which a plurality of warps are adapted to be fed, a reed frame slidably secured to said batten and comprising a plurality of upwardly converging reeds, a slide secured within guides upon said batten, means adapted to swing the batten, a cloth-beam adapted to feed said warps, means connected to a projection on 100 said slide adapted to rotate said cloth beam, upon every swing of said batten, an amount depending upon the relative height of said projection with reference to said batten, an oscillating member adapted to simultaneously raise or lower said reed frame and said slide, a cam adapted to be actuated by said batten to receive a partial rotation with every swing of the latter, and means adapted to be influenced by contact with 105 said cam and to actuate said oscillating member to raise or lower said reed frame and said slide in accordance with the conformation of said cam.

7. In a loom for weaving neckties, in combination, a suspended batten, means for swinging the same, two members secured to said batten adapted to slide up and down thereon, one of said members being adapted to control the width of said tie in every part 115 thereof and the other of said members being adapted to vary the number of weft threads per unit of length of said tie in inverse ratio to changes in the width thereof, means adapted to be actuated by the swing- 120

ing of said batten and to control the simultaneous raising or lowering of said sliding members, and means adapted to limit the downward movement of said second member.

8. In a loom for weaving neckties, in combination, a batten over which a warp is adapted to be fed, provided with shuttles for laying the weft within the warp, 10 means for swinging said batten, a cloth beam, movable means mounted on said batten adapted to drive said cloth beam at different rates of speed, and means actuated by the swinging of said batten for controlling the movement of said movable means.

9. In a loom for weaving neckties, in combination, a batten over which a warp is adapted to be fed, provided with shuttles adapted to lay the weft within the warp, 20 means for swinging said batten, a cloth beam, movable means adapted to be actuated by the swinging of said batten, a member mounted on said batten adapted 25 to transmit motion directly to said movable means, and means for driving said cloth beam adapted to swing with said batten

and to receive from said movable means motion relative to said batten.

10. In a loom for weaving neckties, in combination, a batten over which a warp is adapted to be fed, provided with shuttles adapted to lay the weft within said warp, means for swinging said batten, a fan shaped reed through which said warp passes 35 adapted to be raised and lowered in relation to said batten for changing the width of the warp, a cloth beam adapted to feed said warp, and means adapted to be actuated by the swing of said batten and at 40 predetermined intervals to raise and lower said reed and to vary the movement of said cloth beam, whereby the spacing of the weft threads per unit of length of the tie will be varied simultaneously with the 45 changing of the width thereof by the movement of said reed.

In testimony whereof I affix my signature, in the presence of two witnesses.

GEORGE S. PRUDEN.
